UNITED STATES PATENT OFFICE.

JAKOB DE RYTTER KIELLAND, OF CHRISTIANIA, NORWAY, ASSIGNOR TO BENJAMIN ELECTRIC MANUFACTURING COMPANY, OF CHICAGO, ILLINOIS, A CORPORATION OF ILLINOIS.

LOCKING DEVICE FOR ELECTRICAL CONTACTS.

1,094,907.

Specification of Letters Patent.

Patented Apr. 28, 1914.

Application filed December 12, 1911. Serial No. 665,273.

To all whom it may concern:

Be it known that I, JAKOB DE RYTTER KIELLAND, a subject of the King of Norway, residing at Christiania, Norway, have invented certain new and useful Improvements in Locking Devices for Electrical Contacts; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to a means in contact devices, especially in incandescent lamp holders, for locking the member inserted in the holder, and has for its object to prevent said member from being loosened for instance through shakings or vibrations, or from being wrongfully removed. This latter provision has become of special importance, since the valuable metal wire lamps have come into common use; for it frequently occurs that such lamps are stolen, and often it is not possible to prevent this at distant places without an expensive supervision.

The invention is illustrated in the accompanying drawing, which represents a form of incandescent lamp holder embodying the invention.

Figure 1 is a longitudinal section through the holder, Fig. 2 a plan view of its insulating ring. Fig. 3 illustrates a tool for detaching the lamp.

Fig. 1 by way of example shows an ordinary Edison holder furnished with the said locking device. In the holder the metal member generally formed with screw-threads and serving as a nut for the screw-threads provided on the lamp cap, is entirely or partly replaced by a helical spring *a* of any conductive and elastic material and having such a form that it can serve as a nut for the screw-threads of the glow-lamp cap. The extremity *b* or a portion of the spring is fast with the metal piece connected with the current-carrying contact of the holder, while the other extremity of the spring is free so that the spring may be made to exert its spring action with a shorter or longer portion of its length or with its whole length. Such springs serving to receive the glow-lamp cap are in themselves well

known. According to the present invention; however, the last turns of the spring located near the free end of the same are formed with a smaller diameter than the remaining turns corresponding to the diameter of the screw-threads of the glow-lamp cap.

In screwing in the lamp the spring will open to a certain extent and the cap may be screwed home without difficulty. But if it is now attempted to unscrew the lamp, such operation is rendered impossible, because the spring now acts as a kind of band brake the free end *c*, which firmly engages the screw-threads of the glow-lamp cap, being pulled along with the same so that the spring will thereby be caused to engage the threads always more firmly the greater the force used in attempting to unscrew the lamp, and the lamp would finally burst without being successfully unscrewed. The object mentioned in the preamble, to prevent the incandescent lamp from getting loose or from being wrongfully removed, is thus attained. Now, to enable the lamp to be unscrewed, the holder at its lower portion is furnished with a releasing device which in the present instance is mounted on the insulating ring (Fig. 2) and consists of a small pin or hook *d* which is so arranged as to abut against the end *c* of the spring on being screwed a little further on thereby suspending or reducing the locking action of said spring, in that the latter will thereby be somewhat extended, whereupon the lamp may be unscrewed without difficulty. Even if a thief were acquainted with said releasing device, still it will be very difficult to him to unscrew the lamp. The longer time required is, however, of no consequence in the normal exchange of lamps, as such an exchange only has to take place once in a year or still more unfrequently. Said releasing device may also be provided as a button adjustably mounted on the holder sleeve or in any suitable manner. A wrong-
ful removal of the lamp may also be prevented by using ordinary insulating rings without a projection and employing to release the lamp a tool (Fig. 3) especially adapted for the purpose the extremity *e* (Fig. 3) of the tool, for instance, replacing the pin or projection *d*.

The present invention may of course also be applied to other devices resembling a

lamp holder, for instance to contact couplings and the like in which it is desired to secure the contact or to prevent a wrong-
ful unscrewing operation.

8 It has to be noted that the present invention does not relate to the use of helical springs as a braking means generally, but only, as described, to the use thereof in electric lamp holders and similar electric contacts in conjunction with a device for suspending or reducing the locking action of the spring.

Claims:

1. A device for locking contact-couplings comprising a conductive helical spring serving as a nut for the screw-threads of one of the couplings and having the last turns or part of turn located near the free end of the same formed with a smaller diameter than the remaining turns.

2. A device for locking contact-couplings comprising a conductive helical spring serving as a nut for the screw-threads of one of the couplings and having the last turns or part of turn located near the free end of the same formed with a smaller diameter than the remaining turns, and an insulating ring, having a projection for the unlocking of the spring by a movement against the end of the spring.

3. A locking device of the character described comprising an externally screw-threaded member, a socket, a spiral spring fixed at one end in the socket and adapted

to engage the threads of said member, the free end portion of said spring being of smaller diameter than the other portion, and means to enlarge the smaller diameter, for the purpose specified.

4. A locking device of the character described comprising an externally screw-threaded member, a socket, a spiral spring fixed at one end in the socket and adapted to engage the threads of said member, the free end portion of said spring being of smaller diameter than the other portion, and means adapted to engage the free end of the spring to extend the smaller diameter of the latter, for the purpose specified.

5. A locking device of the character described comprising an externally screw-threaded member, a socket, a spiral spring fixed at one end in the socket and adapted to engage the threads of said member, the free end portion of said spring being of smaller diameter than the other portion, and means on the socket adapted to engage the free end of the spring to extend the smaller diameter of the latter, for the purpose specified.

In testimony that I claim the foregoing as my invention, I have signed my name in presence of two subscribing witnesses.

JAKOB DE RYTTER KIELLAND.
